MOP MAKING APPARATUS

Ernest L. Bennett and Donald F. Burns, Indianapolis, Ind., assignors to J. I. Holcomb Manufacturing Company, Inc., Indianapolis, Ind., a corporation of Indiana

Filed Sept. 21, 1961, Ser. No. 139,763

9 Claims. (Cl. 300—16)

The present invention relates to an apparatus for making mops or swabs such as are used for cleaning toilet bowls and the like.

In the past, the making of swabs has involved, to a large extent, manual operations. Even in situations where apparatus is available for performing some of the operations necessary in swab making, still many operations have been performed manually. Furthermore, certain of these manual operations require the exertion of a relatively great amount of force which presents difficulties especially with female labor. Consequently, one object of the present invention is to provide automatic apparatus for making swabs.

A further object of the present invention is to provide swab making apparatus incorporating automatic means for doubling yarn to be used in the swabs and incorporating automatic means for ejecting the finished swabs from the apparatus.

Related objects and advantages will become apparent as the description proceeds.

One embodiment of the present invention comprises a swab making apparatus including a plurality of cutters, a plurality of handle receiving seats, a yarn supply located adjacent one end of said plurality of seats, means for drawing yarn from said supply through said seats, means for drawing yarn from said supply away from said seats, means for ejecting handles from said seats, and control means for actuating in order said second yarn drawing means, said first yarn drawing means, said cutters, and said handle ejecting means.

The full nature of the invention will be understood from the accompanying drawings and the following description and claims:

FIG. 1 is a side elevation of a handle making up a part of the finished swab.

FIG. 2 is a view of the handle similar to FIG. 1 taken in a different direction.

FIG. 3 is a view similar to FIG. 1 showing the finished swab.

FIG. 4 is a perspective view of swab making apparatus embodying the present invention.

FIG. 5 is a perspective view of the distal end of a piston forming a part of the structure of FIG. 4.

FIG. 6 is a horizontal section through handle receiving seats and cutters forming a part of the structure of FIG. 4, said section being taken generally along line 6—6 of FIG. 4.

FIGS. 7, 8 and 9 are schematic top plan views of the structure of FIG. 4 showing various steps in the operation thereof.

FIGS. 10, 11 and 12 are side elevations of a portion of the frame of the structure of FIG. 4 showing various steps in the ejection of finished swabs from the apparatus.

FIGS. 13 and 14 are schematic views of pneumatic and electrical actuating systems of the present invention.

For the purposes of promoting an understanding of the principles of the invention, reference will now be made to the embodiment illustrated in the drawing and specific language will be used to describe the same. It will nevertheless be understood that no limitation of the scope of the invention is thereby intended, such alterations and further modifications in the illustrated device, and such further applications of the principles of the invention as illustrated therein being contemplated as would normally

2

occur to one skilled in the art to which the invention relates.

Referring to FIGS. 1-3, it can be seen that the swab produced by the present invention comprises a handle 10 having a ring or circular portion 11 formed integrally on one end thereof. In making the swab, yarn 12 (preferably plastic fibers known as acrilan) are drawn through the ring 11 and are cut off to form the ball shape illustrated in FIG. 3. It has been found that by merely cutting a length of such yarn extending through the ring 11 with a straight cut, the natural fluffing out of the yarn produces the desired curved ball shape shown in FIG. 3.

Referring to FIG. 4, the swab making apparatus embodying the present invention comprises a frame 14 having a plurality of side-by-side blocks 15 fixed thereto. Each of the blocks 15 has an upwardly opening, generally C-shape which is aligned with adjacent blocks to provide a central channel 16 for the passage therethrough of yarn and of a piston rod 17. In the illustrated embodiment, four of the blocks 15 are provided, however, it should be understood that any suitable number such as eight or ten, if desired, can be used. Each of the blocks 15 is provided with an indentation 20 formed to snugly receive handle 10 and an indentation 21 suitably formed to snugly receive the ring end 11 of the handle 10.

A reel 22 of yarn is rotatably mounted upon a lower table 25 forming a part of the frame and provides a yarn supply through the opening 26 in an upper table 27. As mentioned, the piston rod 17 is movable or extensible through the channel 16 in the various blocks 15. In alignment with the channel 16 is an opening 30 in the upright 29 forming part of the frame 10, this opening 30 being adjacent the opening 26 in the table 27. By suitable operation of the pneumatic piston 31, the piston rod 17 thereof may be extended through the channel 16 and through the opening 30. For a reason that will be evident below, the opening 30 tapers from a larger end at the face 33 of member 29 to a smaller end at the hidden face thereof (as viewed in FIG. 4).

The distal end of the piston rod 17 is formed in the peculiar manner illustrated in FIG. 5 and includes a slot 32 which leads into angularly extending bores 35. A flexible length of wire 36 or the like (FIG. 6) having balls 37 fixed on the end thereof is used with the slot 32 and the bores 35 to secure a loop 40 of yarn to the distal end of the piston rod 17. This yarn may then be drawn through the channel 16 toward the cylinder of the piston 31.

Both the piston motor 31 and a further piston motor 41 are mounted in parallel relation upon a table 42 forming a part of the frame. Both piston motors 31 and 41 have an equal stroke. The piston rod 42, however, is relatively long so that, when retracted, its end is located just to the left of the block 45. The block 45, as well as the block 46, are fixed to table 27 and provide a mount for parallel bars 47 along which a carriage 50 is slidably, said carriage including side plates 49 mounting bearings 48 received on shafts 47. The piston rod 42 of the piston 41 is fixed to one side plate 49 of carriage 50, provides a motive force thereto and is slidable through the block 45.

The carriage 50 has mounted thereon clamping jaws 51 and 52, jaw 52 being fixed to the side plates 49 by bottom plate 55 and jaw 51 being movable by means of a piston motor 56 fixed to the carriage. It can be appreciated that when the piston rod 69 of the piston motor 56 is extended, the jaw 51 will engage or be forced towards the jaw 52 to clampingly engage the yarn 62.

The frame 14 further includes vertical side member 65 parallel to side member 29, said side members having 70 fixed to their upper ends a horizontal top piece 66. Secured to the top piece is a pneumatic cylinder 67 hav-

ing its piston 68 fixed to a cutter carriage 70. Fixed to the upper surface of the carriage 70 is a pair of angles 71 which have shafts 72 rotatably mounted therethrough. At the opposite ends of these shafts are fixed spur gears 75, the shafts being spaced sufficiently in order to permit rotation of each shaft without interference with the gears of the opposite parallel shaft.

As the carriage 70 is moved upwardly and downwardly by the pneumatic piston 67, the gears 75 travel up and down racks 76 fixed to the inside surfaces of the vertical members 29 and 65. The shafts, gear, and rack assembly, 72, 75 and 76 maintain the carriage in a horizontal position at all times. It can be appreciated that the gear 75 at one end of the carriage and on a given shaft 72 cannot move vertically to a greater extent than the gear on the same shaft at the other end of the carriage because the gears 75 all have the same diameter and the same number of equal sized teeth and racks 76 are also identical. Thus, the carriage is always maintained horizontal during its vertical movement.

Fixed to the bottom of the carriage 70 is a plurality of cutter blades 77 which travel between parallel plates 80 and 81 (FIGS. 4 and 6). Each of the plates 80 and 81 is formed with a bore in alignment with and forming a part of the channel 16. Each of the plates 80 is formed at the lower edge of its bore with a cutting edge which cooperates with a respective one of the cutter blades 77 for shearing the loop of yarn 40.

Frame 14 further includes a table 82 fixedly mounted between the vertical upright side members 29 and 65. Resting upon this table is a horizontal bar 85 which is used to eject the finished swabs after they have been provided with their yarn as in FIG. 3. The horizontal bar 85 is vertically movable within guides 86 fixed to the respective side members 29 and 65 and providing vertically extending apertures through which the horizontal bar 85 can move. Upon each side of the carriage 70 is mounted a latch assembly 87. A representative one of these latch assemblies is shown in FIGS. 10-12 in various positions occurring during the operation thereof.

Referring to FIGS. 10-12, there is illustrated a latch member 90 pivotally mounted at 91 upon the carriage 70. In FIG. 10, the carriage 70 is shown in its lowermost position wherein the latching surface 92 of the latch member 90 is below the horizontal bar 85. The latch member 90 is formed with a tapering surface 95 which permits the latch member to pivot out around the bar 85 as the carriage 70 moves downwardly. A compression spring 96 operates between the upper end 97 of the latching member and the mounting element 100 fixed to the side member 29. The spring 96 yieldably holds the latching member with its lower end in a leftward direction as illustrated in FIGS. 10-12.

The latching member has a cam 101 formed thereon which cooperates with a cam 102 fixed to the side member 29. Referring to FIGS. 11 and 12, when the carriage 70 moves upwardly, the cam 101 engages the cam 102 to pivot the lower end of the latching member rightwardly to drop the horizontal bar 85 as shown in FIG. 12. This dropping action does not occur, however, until the bar has been raised a sufficient distance to raise and thoroughly loosen and eject the finished handles from their seats as formed by the blocks 15. It can be appreciated that because the latch assemblies 87 are mounted upon the carriage 70, the cutting operation always occurs prior to the ejecting operation. In other words, the carriage 70 always starts from and returns to an upward position.

The structure illustrated in FIGS. 7-9 will be described in connection with a description of the operation of the present device. In order to operate the device, the handles such as illustrated in FIGS. 1 and 2 are inserted into the machine into the position shown in FIGS. 4 and 6 wherein the rings 11 are in alignment with the channel 16. A conventional pneumatic hand valve 105 is then operated to provide air pressure simultaneously to the pistons 31

and 41. The pneumatic system is so arranged that operation of the valve 105 in one direction causes the piston rods of both pistons to be simultaneously extended. Since the clamping device 50 is engaging the yarn 62, the extension of the piston rod 42 causes the yarn to be drawn as suggested in FIG. 4 leftwardly until the carriage 50 reaches the leftward end of its travel. The travel of the carriage is such that the yarn 62 is drawn out to an extent whereby the length of the drawn-out yarn, taken from opening 26 to clamping device 50, is equal to the travel of the piston rod 17.

Simultaneously, with the extension of piston rod 42, the piston rod 17 is extended until it projects leftwardly as viewed in FIG. 4 through and out of the bore 30 in the side member 29. When the carriage 50 reaches the leftward end of its travel, it engages a limit switch 106 (FIGS. 7-9) mounted on the upper table 27. Engagement of this limit switch operates an air valve 108 (FIG. 14) reversing it and causing retraction of the piston rod 60 of the piston motor 56, thus releasing the clamping action on the yarn 62. The operator then, by means of the flexible wire 36 and the balls 37 on the end thereof, attaches that portion of the yarn which is then at the opening 26 to the end of the piston rod 17.

The hand valve 105 is then reversed causing retraction of both piston 42 and 17. The retraction of the two piston rods causes the yarn to be drawn in a doubled relation (from the portion 62 and reel 22) through the bore 30 and the channel 16 and also causes the clamping device 51 to be moved rightwardly to a position adjacent the bore 30 where it is ready to clamp yarn. The tapered configuration of the opening 30 reduces the size of the doubled loop of yarn without cutting or tearing thereof. A further limit switch 107 mounted on the frame 10 (FIGS. 7-9) is engaged and actuated by the actuating arm 110 fixed to the piston rod 42. The limit switch 107 actuates an air valve 109 controlling the air pressure to the pneumatic cylinder 67 causing the carriage 70 to be moved downwardly and the cutter blades 77 to cut through the yarn. The actuation of limit switch 107 also causes the valve controlling air to the piston 56 to be reversed to cause actuation of the clamping device 51 whereby the yarn is clamped at or adjacent the indentation 26. It will be appreciated that the yarn will be extending between the opening 26 and the opening 30 so that the jaws of the clamping device will pass on opposite sides of the yarn prior to the closing of the jaws.

A further limit switch 111 is provided which is in the path of the carriage 70. When the carriage reaches its lowermost position, the limit switch is actuated causing reversal of the valve controlling air pressure to the pneumatic cylinder 67 whereby the piston rod 68 reverses the direction of the carriage. As explained above, the upward movement of the carriage 70 causes the bar 85 to be raised thus ejecting the finished handles from the apparatus.

Referring to FIG. 13, there is illustrated the pneumatic system of actuation of the cylinders 31 and 41. As mentioned on page 11, the hand valve 105 may be operated in two directions. When the hand valve is operated in one direction, the piston rods 17 and 42 are simultaneously extended by reason of the fact that the pneumatic inlet 150 is connected to one end 151 and 152 of the pneumatic cylinders 31 and 41 by means of a forked conduit 155. When the valve 105 is in said position, the other ends 156 and 157 of the cylinders 31 and 41 are connected to atmosphere through the forked conduit 160, the valve 105 and the outlet 161. When the valve 105 is reversed as mentioned in column 4, line 25, the two piston rods 17 and 42 are retracted by the connection of the pneumatic inlet 150 to the ends 156 and 157 of the cylinders 41 and 31 through the conduit 160. The ends 151 and 152 of the cylinders 31 and 41 are connected to atmosphere through the conduit 155, the valve 105 and the conduit 161.

Referring to FIG. 14, the electrical pneumatic system

of the present embodiment is further disclosed. The pneumatic cylinder 56 is connected to the valve 108 by conduits 162 and 165, the conduit 162 leading into one end 166 of the cylinder 56 and the conduit 165 leading into the other end 167 thereof. As mentioned above, the limit switches 106 and 107 control the valve 108. When the limit switch 106 is actuated by the carriage 50, the valve 108 connects the pneumatic inlet 170 to the conduit 162 and also connects the conduit 171 which leads to atmosphere to the conduit 165. Thus, pressure acts upon the piston of the cylinder 56 retracting the piston rod 60 and releasing the clamping action on the yarn 62. When the carriage 50 moves to the other end of its travel causing the actuator 110 to engage the limit switch 107, the electrical leads 172 carry energy to the valve 108 which reverses the valve 108 and connects the conduit 162 to atmosphere and the conduit 165 to the inlet pressure from the conduit 170. Such reversal of the valve 108 causes the piston 60 of the motor 56 to be projected and to clamp the yarn at the yarn supply 26.

The actuation of the limit switch 107 also causes electrical energy to move through the leads 175 actuating the valve 109 to connect the pneumatic inlet conduit 176 with the conduit 177 causing pneumatic pressure to be conducted to the upper end of the motor 67. When the valve 109 is in such position, the lower end 180 of the cylinder 67 is connected to atmosphere through the conduit 181. As explained above, the carriage 70 moves downwardly until the limit switch 111 is actuated. Engagement of the limit switch 111 actuates the valve 109 through electrical leads 182 connecting the valve and limit switch whereby the valve is reversed and the pressure conduit 176 is connected to the conduit 181 leading pressure into the bottom of the cylinder. The upper end of the cylinder is connected to atmosphere through the conduit 177, the valve 109 and the conduit 183.

From the above description, it will be obvious that the present invention provides an improved, highly automatic apparatus for making swabs. It will also be obvious that the present invention provides swab making apparatus incorporating automatic means for doubling the yarn to be used in the swabs and also incorporates automatic means for ejecting the finished swabs from the apparatus.

While the invention has been illustrated and described in detail in the drawings and foregoing description, the same is to be considered as illustrative and not restrictive in character, it being understood that only the preferred embodiment has been shown and described and that all changes and modifications that come within the spirit of the invention and the scope of the claims are also desired to be protected.

The invention claimed is:

1. Swab making apparatus comprising a plurality of cutters, a plurality of handle receiving seats each positioned between a pair of said cutters, a yarn supply located adjacent one end of said plurality of seats, means for drawing yarn from said supply through said seats, means for drawing yarn away from said yarn supply, means for ejecting handles from said seats, and control means for actuating in order for sequential operation said second yarn drawing means, said first yarn drawing means, said cutters and said handle ejecting means.

2. Swab making apparatus comprising a plurality of cutters, a plurality of handle receiving seats each positioned between a respective pair of said cutters, a piston motor having a piston rod extensible and retractable through said seats, connecting means at the distal end of the piston rod for attaching a loop of yarn thereto whereby retraction of said piston rod draws yarn through said seats, each of said cutters having cutting edges positioned on opposite sides of the path of the connecting means for the cutting of said yarn, a yarn supply at the piston-rod-extended end of the connecting means path, a further piston motor having a further piston rod, and a yarn clamping device mounted on the distal end of said further

piston rod, said further piston rod being movable by said further piston motor to move said clamping device between said yarn supply and a position removed from said yarn supply by a distance equal to the travel of said first piston rod.

3. Swab making apparatus comprising a plurality of cutters, a plurality of handle receiving seats each positioned between a respective pair of said cutters, a piston motor having a piston rod extensible and retractable through said seats and through handles received in said seats, connecting means at the distal end of the piston rod for attaching yarn thereto whereby retraction of said piston rod draws yarn through said seats, each of said cutters having cutting elements positioned on opposite sides of the path of the connecting means for the cutting of said yarn, a yarn supply at the piston-rod-extended end of the connecting means path, a further piston motor having a further piston rod arranged to travel parallel to said first piston rod, a yarn clamping device mounted on the distal end of said further piston rod, said further piston rod being movable by said further piston motor to move said clamping device between said yarn supply and a position removed from said yarn supply by a distance equal to the travel of said first piston rod, control means arranged to extend and retract said piston rods simultaneously, and further control means arranged to actuate said clamping device to clamp yarn at said yarn supply when said piston rods are retracted and to unclamp yarn when said piston rods are extended.

4. Swab making apparatus comprising a plurality of cutters, a plurality of handle receiving seats each positioned between a respective pair of said cutters, a piston motor having a piston rod extensible and retractable through said seats, connecting means at the distal end of the piston rod for attaching yarn thereto whereby retraction of said piston rod draws yarn through said seats, each of said cutters having cutting elements positioned on opposite sides of the path of the connecting means for the cutting of said yarn, a yarn supply at the piston-rod-extended end of the connecting means path, a further piston motor having a further piston rod, a yarn clamping device mounted on the distal end of said further piston rod, said further piston rod being movable by said further piston motor to move said clamping device between said yarn supply and a position removed from said yarn supply by a distance equal to the travel of said first piston rod, control means arranged to extend and retract said piston rods simultaneously, and further control means arranged to actuate said clamping device to clamp yarn at said yarn supply when said piston rods are retracted and to unclamp yarn when said piston rods are extended.

5. Swab making apparatus comprising a frame, a pair of piston motors mounted on said frame, said piston motors having piston rods arranged to extend and retract simultaneously, said frame having a plurality of handle receiving seats along the path of one of said piston rods,

55 connecting means at the distal end of one piston rod for attaching yarn thereto, a yarn supply at the extended end of the one piston rod's path, a yarn clamping device mounted at the distal end of said other piston rod, said other piston rod being movable by its piston motor to position said clamping device at said yarn supply when the piston rods are retracted and to position said clamping device a distance away from said yarn supply equal to the travel of said connecting means when the piston rods are extended, cutting means mounted on said frame and interposed between the respective handle receiving seats, and control means arranged to actuate said clamping device to release yarn upon extension of said piston rods and to clampingly engage yarn at said yarn supply upon retraction of said piston rods, said control means being further arranged to actuate said cutting means upon retraction of said piston rods.

6. Swab making apparatus comprising a frame, a plurality of cutters mounted on said frame, each of said cutters including a cutting edge fixed with relation to said frame and a cutting edge movable with respect to said frame, a carriage having each of said movable cutting

edges mounted thereon for movement therewith, said carriage being vertically movable on said frame, said frame having a plurality of handle receiving seats each positioned between a respective pair of said cutters, a piston mounted on said frame, said piston having a piston rod extensible and retractable through said seats, connecting means at the distal end of the piston rod for attaching yarn thereto whereby retraction of said piston rod draws yarn through said seats, a bar mounted for vertical movement on said frame, said bar being adjacent said seats and movable upwardly to eject handles from said seats, a latch pivotally mounted on said carriage, resilient means arranged to urge said latch into latching relation with said bar when said carriage is in a downward position whereby upward movement of said carriage causes said bar to eject handles, and a cam fixed to said frame and positioned to actuate said latch during upward movement to disengage said bar, said bar being normally urged downwardly by gravity.

7. Swab making apparatus comprising a frame, a plurality of cutters mounted on said frame, each of said cutters including a cutting edge fixed with relation to said frame and a cutting edge movable with respect to said frame, a carriage having each of said movable cutting edges mounted thereon for movement therewith, said carriage being vertically movable on said frame, said frame having a plurality of handle receiving seats each positioned between a respective pair of said cutters, a piston motor mounted on said frame, said piston motor having a piston rod extensible and retractable through said seats, connecting means at the distal end of the piston rod for attaching yarn thereto whereby retraction of said piston rod draws yarn through said seats, a yarn supply located adjacent the position of said connecting means when said piston rod is extended, a further piston motor having a further piston rod, a clamping device mounted on the distal end of said further piston rod, said further piston

motor being adapted to move said clamping means between a first position at said yarn supply and a second position removed from said yarn supply, control means for closing said clamping means during movement from said first to said second position and opening said clamping means during movement from said second to said first position, a bar mounted for vertical movement on said frame, said bar being adjacent said seats and movable upwardly to eject handles from said seats, a latch pivotally mounted on said carriage, resilient means arranged to urge said latch into latching relation with said bar when said carriage is in a downward position whereby upward movement of said carriage causes said bar to eject handles, and a cam fixed to said frame and positioned to actuate said latch during upward movement to disengage said bar, said bar being normally urged downwardly by gravity.

8. Swab making apparatus comprising a plurality of cutters, a plurality of handle receiving seats each positioned between a pair of said cutters, a yarn supply located adjacent one end of said plurality of seats, means for drawing yarn from said supply through said seats, means for ejecting handles from said seats, and control means for actuating in order for sequential operation said yarn drawing means, said cutters and said handle ejecting means.

9. Swab making apparatus comprising a plurality of cutters, a plurality of handle receiving seats each positioned between a pair of said cutters, a yarn supply located adjacent one end of said plurality of seats, means for drawing yarn from said supply through said seats, means for drawing yarn from said supply away from said seats, and control means for actuating in order for sequential operating said second yarn drawing means, said first yarn drawing means and said cutters.
